Inventor:
by Max Hackländer
Mr. Wallace White
Atty.

UNITED STATES PATENT OFFICE.

MAX HACKLÄNDER, OF NEVIGES, GERMANY.

PADLOCK.

Application filed September 26, 1922. Serial No. 590,592.

To all whom it may concern:

Be it known that I, MAX HACKLÄNDER, citizen of the Republic of Germany, residing at Neviges, Rhineland, Germany, have 5 invented new and useful Improvements in Padlocks, of which the following is a specification.

This invention relates to padlocks whose casing is enclosed in protective shells or 10 armor of hard metal. Hitherto the armor of padlocks has been made of pieces of pressed or cast metal which were fastened to the enclosed casing of the padlock by rivets, screws or any other preferred fastening 15 means and this involved considerable expenditure for labor without excluding the possibility of undoing the fastening means or forcing off the armor by means of explosives and thus depriving the lock of its 20 protective coating.

The object of this invention is to provide locks with seamless armor, i. e., with a protective shell consisting of only one piece and enclosing the entire mechanism of the 25 padlock. The armor has only one opening for the key of the lock and two other openings for the staple or bow of the same.

Locks with seamless armor of this kind are produced by first fitting the mechanism 30 of the lock into a rough, thin, sheet metal casing and then inserting this casing in a chill-mold so that the casing forms a core in the mold. Auxiliary cores are introduced through the walls of the chill-mold and 35 penetrate into the thin metal casing. These auxiliary cores suspend the lock in the proper position in the interior of the chill-mold and when the cast metal, which forms the armor, is poured in, it completely covers 40 the sheet metal casing, except at points where the auxiliary cores are situated, holes being thus formed in the armor by the auxiliary cores, the one hole forming the key-hole and the two other holes serving to 45 receive the ends of the staple or bow of the padlock. After the shell, as of aluminium, has been cast round the lock and after the molten metal has hardened the auxiliary cores which are attached to levers, are 50 pulled out and after the top part of the chill-mold is lifted the encased lock will be exposed to view.

Apart from the greatest security ob-

tained, locks with seamless armor offer a number of other advantages over such as 55 are encased in a covering consisting of several parts. The internal sheet metal casing into which the mechanism of the lock is fitted need not be carefully made so as to secure a pleasing external appearance of the 60 same. The heads of the rivets which hold the primary or internal casing together, and determine the distance between the walls of the lock casing, need not be placed in countersunk holes, which is necessary to afford 65 security in ordinary locks, because they are completely covered in by the metal afterwards cast round the casing and have nothing to do with the external appearance of the lock. The shrinking of the cast metal 70 covering results in the entire mechanism of the lock being firmly held so that all loosening of the rivets and screw, which would be liable to take place when the lock is 75 constantly subjected to vibrations, is entirely precluded.

The invention is shown in the drawing in which—

Fig. 1 is a cross section of the chill-mold and an enclosed lock on the line A—B of 80 Fig. 2 and

Fig. 2 is a plan view of the mold.

The chill-mold, in which the coating or armor is cast round the padlock, consists of a bottom plate 5 and an upper plate 2 with 85 a mouth 7 into which the cast metal is poured. The top half 2 of the mold is provided with handles 3. Levers 4 are provided for pulling out the auxiliary cores 6 and 8, the ends of the cores 6 penetrating 90 into the primary or internal casing 1 of the padlock, and the inner end of the core 8 penetrating into the opposite side of this casing. The cores 6 and 8 hold the internal 95 casing 1 of the lock with its mechanism suspended in the chill-mold so that when liquid metal is poured in it will completely envelop the casing 1 except where the auxiliary cores 6 and 8 form holes for the key and the ends of the bow of the padlock. 100

I claim:—

1. Process for forming a seamless shell on a lock consisting in suspending the lock in a chill-mold by means of auxiliary cores and thereupon pouring metal into the mold. 105
2. Process for forming a seamless shell

on padlocks consisting in suspending the lock in a chill-mold by means of auxiliary cores adapted to form holes in the shell for the bow and key of the padlock, and pouring metal into the mold in which the padlock is suspended.

In testimony whereof I have signed my

name to this specification in the presence of two subscribing witnesses.

MAX HACKLÄNDER.
